ABSTRACT

A liquid ejecting head includes a nozzle plate, a multilayer substrate, and a pressure chamber substrate. The multilayer substrate includes a liquid chamber wall portion. The liquid chamber wall portion has a first wall surface facing a common liquid chamber. The multilayer substrate has a supply flow path which has an inlet portion coupled to the first wall surface and via which the common liquid chamber communicates with the first pressure chamber. When a direction from the common liquid chamber toward the first pressure chamber is defined as a first direction, and a direction intersecting the first direction is defined as a second direction, the supply flow path includes a first portion having a first width in the inlet portion and a second portion having a second width, in a first cross section along the first direction and the second direction. The first width is narrower than the second width.

COMPARATIVE EXAMPLE## LIQUID EJECTING HEAD AND LIQUID EJECTING APPARATUS

The present application is based on, and claims priority from, JP Application Serial Number 2018-117507, filed Jun. 21, 2018, the disclosure of which is hereby incorporated by reference herein in its entirety.

BACKGROUND

1. Technical Field

The present disclosure relates to a liquid ejecting head and a liquid ejecting apparatus.

2. Related Art

For example, the liquid ejecting head described in JP-A-2015-30153 has a structure in which a nozzle plate having a nozzle, a flow path substrate having a nozzle communication flow path coupled to the nozzle of the nozzle plate, and a pressure chamber substrate having a pressure chamber coupled to the nozzle communication flow path of the flow path substrate are laminated in order. The flow path substrate has a common liquid chamber for supplying a liquid to a plurality of pressure chambers and a supply flow path via which the common liquid chamber communicates with each pressure chamber. The liquid ejecting head ejects a liquid droplet from the nozzle by causing a pressure change in the liquid in the pressure chamber. The liquid is supplied to each pressure chamber from the common liquid chamber via the supply flow path.

When a plurality of supply flow paths are formed in the flow path substrate by etching, a wall surface of a portion from the common liquid chamber toward each supply flow path may have a "sagging shape" in which the wall surface is lowered to the supply flow path side. The term "sagging" means drooping, for example, a tip end is lowered. The sagging shape of an inlet portion of the supply flow path is a shape in which the wall surface of the inlet portion of the supply flow path is expanded.

When the inlet portion of the supply flow path has the sagging shape, a bubble adhering to the wall surface of the inlet portion of the supply flow path may be difficult to be discharged at the time of cleaning. The bubble remaining in the supply flow path affects the ejection of the liquid droplet, so that it is necessary to suppress the residual bubbles in the supply flow path.

SUMMARY

According to an aspect of the present disclosure, there is provided a liquid ejecting head including a nozzle plate that includes a nozzle, a multilayer substrate that includes a first flow path arrangement layer and a second flow path arrangement layer in an order of arrangement from a side of the nozzle plate, and includes a nozzle communication flow path and a common liquid chamber, and a pressure chamber substrate that includes a first pressure chamber communicating with the nozzle via the nozzle communication flow path and a second pressure chamber disposed next to the first pressure chamber via a partition wall, in which the common liquid chamber communicates with the first pressure chamber and the second pressure chamber, the multilayer substrate includes a liquid chamber wall portion disposed on a side of the second flow path arrangement layer from the common liquid chamber, the liquid chamber wall portion

includes a first wall surface facing the common liquid chamber, the multilayer substrate includes a supply flow path via which the common liquid chamber communicates with the first pressure chamber and has an inlet portion coupled to the first wall surface, when a direction from the common liquid chamber toward the first pressure chamber is defined as a first direction and a direction intersecting the first direction is defined as a second direction, the supply flow path includes a first portion having a first width in the inlet portion and a second portion having a second width in a first cross section along the first direction and the second direction, and the first width is narrower than the second width.

In addition, a liquid ejecting apparatus of the present disclosure has an aspect that includes the liquid ejecting head.

BRIEF DESCRIPTION OF THE DRAWINGS

20 FIG. 1 is a view schematically illustrating an example of a liquid ejecting head in a cross section along an X direction and a Z direction.

FIG. 2 is an enlarged cross-sectional view of a portion II in FIG. 1.

25 FIG. 3 is a view schematically illustrating an example of the liquid ejecting head in a cross section along a Y direction and the Z direction.

FIG. 4 is a plan view schematically illustrating an example of a multilayer substrate as viewed from a pressure chamber substrate.

30 FIG. 5 is a view schematically illustrating an example of a cross section of the multilayer substrate at a position of V-V in FIG. 4.

FIG. 6A is a view schematically illustrating an example of a cross section of a supply flow path at a position of VIA-VIA in FIG. 5, and FIG. 6B is a view schematically illustrating an example of a cross section of the supply flow path at a position of VIB-VIB in FIG. 5.

FIGS. 7A to 7C are cross-sectional views schematically illustrating an example of a manufacturing step of the liquid ejecting head.

FIGS. 8A to 8C are cross-sectional views schematically illustrating an example of the manufacturing step of the liquid ejecting head.

FIGS. 9A to 9C are cross-sectional views schematically illustrating an example of the manufacturing step of the liquid ejecting head.

FIGS. 10A and 10B are cross-sectional views schematically illustrating an example of the manufacturing step of the liquid ejecting head.

FIG. 11 is a cross-sectional view schematically illustrating an example in which a first flow path arrangement layer and a second flow path arrangement layer in a nozzle communication flow path corresponding region are etched.

55 FIG. 12 is a view schematically illustrating another example of a manufacturing method.

FIG. 13 is a cross-sectional view schematically illustrating another example of the manufacturing step.

FIG. 14 is a view schematically illustrating another example of the manufacturing method.

FIGS. 15A to 15C are cross-sectional views schematically illustrating another example of the manufacturing step.

FIG. 16 is a perspective view schematically illustrating an example of a liquid ejecting apparatus having the liquid ejecting head.

65 FIG. 17 is a view schematically illustrating another example of a cross section of the multilayer substrate.

FIG. 18 is a view schematically illustrating another example of the manufacturing step.

FIGS. 19A and 19B are cross-sectional views schematically illustrating another example of the manufacturing step.

FIGS. 20A and 20B are cross-sectional views schematically illustrating another example of the manufacturing step.

FIGS. 21A and 21B are cross-sectional views schematically illustrating another example of the manufacturing step.

FIGS. 22A and 22B are cross-sectional views schematically illustrating another example of the manufacturing step.

FIGS. 23A to 23C are cross-sectional views schematically illustrating an example of a manufacturing step of a liquid ejecting head according to a comparative example.

DESCRIPTION OF EXEMPLARY EMBODIMENTS

Hereinafter, embodiments of the present disclosure will be described. As a matter of course, the following embodiments merely exemplify the present disclosure, and not all of the features described in the embodiments are necessarily essential to the solution means of the disclosure.

(1) Outline of Technology Included in Present Disclosure:

First, an outline of the technology included in the present disclosure will be described with reference to the examples illustrated in FIGS. 1 to 23. The drawings of the present application are views schematically illustrating examples, the enlargement ratios in the respective directions illustrated in these drawings may be different from each other, and the respective drawings may not be matched in some cases. As matter of course, each element of the present technology is not limited to a specific example indicated by a reference numeral.

In addition, in the present application, the numerical range "Min to Max" means the minimum value Min or more and the maximum value Max or less. The compositional ratio represented by the chemical formula represents the stoichiometric ratio, and substances represented by the chemical formula include those deviating from the stoichiometric ratio.

Aspect 1

A liquid ejecting head 1 according to an aspect of the present technology includes a nozzle plate 80, a multilayer substrate 30, and a pressure chamber substrate 10. The nozzle plate 80 has a nozzle 81. The multilayer substrate 30 includes a first flow path arrangement layer 131 and a second flow path arrangement layer 132 in an order of arrangement from a side of the nozzle plate 80. The multilayer substrate 30 has a nozzle communication flow path and a common liquid chamber 40. The pressure chamber substrate 10 has a first pressure chamber 121 communicating with the nozzle 81 via the nozzle communication flow path 31 and a second pressure chamber 122 disposed next to the first pressure chamber 121 via a partition wall 12a. The common liquid chamber 40 communicates with the first pressure chamber 121 and the second pressure chamber 122.

The multilayer substrate 30 includes a liquid chamber wall portion 33 disposed on a side of the second flow path arrangement layer 132 from the common liquid chamber 40. The liquid chamber wall portion 33 has a first wall surface 33a facing the common liquid chamber 40. The multilayer substrate 30 has a supply flow path 32 via which the common liquid chamber 40 communicates with the first pressure chamber 121 and has an inlet portion coupled to the first wall surface 33a.

Here, a direction from the common liquid chamber 40 toward the first pressure chamber 121 is defined as a first

direction D1, and a direction intersecting the first direction D1 is defined as a second direction D2. As exemplified in FIG. 6A and the like, the supply flow path 32 includes a first portion 310 having a first width W1 in the inlet portion and a second portion 320 having a second width W2, in a first cross section SC1 along the first direction D1 and the second direction D2. The first width W1 is narrower than the second width W2.

In the above aspect 1, since the width of the supply flow path 32 is narrower than the second portion 320 at the inlet portion from the common liquid chamber 40 in the first cross section SC1, a bubble adhering to the wall surface of the inlet portion of the supply flow path 32 are likely to be discharged at the time of cleaning. Therefore, according to this aspect, it is possible to provide the liquid ejecting head that improves a discharge performance of the bubbles of the supply flow path.

Here, the nozzle is a small hole which a liquid droplet such as an ink droplet ejects.

The pressure chamber is a space for applying pressure to the liquid in the inside.

The liquid ejecting head is also called a liquid discharge head.

The above-described appendix also applies to the following aspects.

Aspect 2

The multilayer substrate 30 may include an insulating layer 141 having a material different from a material forming the first flow path arrangement layer 131 and a material forming the second flow path arrangement layer 132 between the first flow path arrangement layer 131 and the second flow path arrangement layer 132. As exemplified in FIG. 5 and the like, the first portion 310 may include a first facing portion 311 protruding inside the supply flow path 32 compared with the second portion 320 at a position including the insulating layer 141. The supply flow path 32 may include a first inclined portion 340 having a second wall surface 341 inclined with respect to the first direction D1 between the first facing portion 311 and the second portion 320. According to this aspect, since the first inclined portion 340 is provided between the first facing portion 311 and the second portion 320 in the supply flow path 32, the flow of a liquid Q1 improves and the residual bubbles in the supply flow path 32 are further suppressed. Therefore, according to this aspect, it is possible to provide a technology for further improving the discharge performance of the bubbles of the supply flow path.

Here, as the material forming the first flow path arrangement layer and the second flow path arrangement layer, a semiconductor such as silicon, metal, ceramics, or the like can be used. As the material forming the insulating layer, a material different from the materials forming the first flow path arrangement layer and the second flow path arrangement layer can be used from among silicon oxide, metal oxide, ceramics, synthetic resin, and the like. For example, when an SOI substrate is used for the multilayer substrate, an insulating layer can be formed from the silicon oxide layer and the first flow path arrangement layer and the second flow path arrangement layer can be formed from the silicon layers on both sides of the above-described silicon oxide layer. SOI is an abbreviation for "silicon on insulator".

The insulating layer of the multilayer substrate is not limited to one layer and may be two or more layers.

The above-described appendix also applies to the following aspects.

Aspect 3

In addition, the first portion **310** may include a second facing portion **312** protruding inside the supply flow path **32** from the liquid chamber wall portion **33** at a position facing the first facing portion **311**. According to this aspect, it is possible to provide a technology for further improving the discharge performance of the bubbles of the supply flow path.

Aspect 4

Furthermore, the supply flow path **32** may include a second inclined portion **350** having a third wall surface **351** inclined with respect to the first direction **D1** between the second facing portion **312** and the second portion **320**. According to this aspect, since the second inclined portion **350** is provided between the second facing portion **312** and the second portion **320** in the supply flow path **32**, the flow of the liquid **Q1** improves and the residual bubbles in the supply flow path **32** are further suppressed. Therefore, according to this aspect, it is possible to provide a technology for further improving the discharge performance of the bubbles of the supply flow path.

The fact that the wall surfaces of the first inclined portion **340** and the second inclined portion **350** are inclined with respect to the first direction **D1** means that the wall surfaces of the first inclined portion **340** and the second inclined portion **350** are not along the first direction **D1** and the wall surfaces of the first inclined portion **340** and the second inclined portion **350** are not orthogonal to the first direction **D1**.

The inclined wall surface of the supply flow path may be located between the first portion **310** and the second portion **320** in the first cross section **SC1**. Therefore, in a cross section along the first direction **D1** and not along the second direction **D2**, the inclined wall surface may not be present in the supply flow path **32**, or the inclined wall surface may be present in the supply flow path **32**.

The above-described appendix also applies to the following aspects.

Aspect 5

As exemplified in FIG. 6A, a shape of the second portion **320** in a second cross section **SC2** orthogonal to the first direction **D1** may have a first angle **AN1** and a second angle **AN2** facing the first angle **AN1**. As exemplified in FIG. and the like, the first inclined portion **340** may be disposed in a direction **D3** opposite to the first direction **D1** from the first angle **AN1**.

In the above aspect, since the first inclined portion **340** is located at a position corresponding to the first angle **AN1** when the supply flow path **32** is viewed from the first direction **D1**, the residual bubbles of the supply flow path **32** are further suppressed. Therefore, according to this aspect, it is possible to provide a technology for further improving the discharge performance of the bubbles of the supply flow path.

Aspect 6

In addition, as exemplified in FIG. 5 and the like, the second inclined portion **350** may be disposed in a direction **D3** opposite to the first direction **D1** from the second angle **AN2**.

In the above aspect, since the first inclined portion **340** is located at a position corresponding to the first angle **AN1** and the second inclined portion **350** is located at a position corresponding to the second angle **AN2** when the supply flow path **32** is viewed from the first direction **D1**, the residual bubbles of the supply flow path are further suppressed. Therefore, according to this aspect, it is possible to

provide a technology for further improving the discharge performance of the bubbles of the supply flow path.

Aspect 7

Furthermore, the first angle **AN1** and the second angle **AN2** may be acute angles. In the above aspect, since the first inclined portion **340** is located at a position corresponding to the first angle **AN1** when the supply flow path **32** is viewed from the first direction **D1**, the residual bubbles of the supply flow path **32** are further suppressed. Therefore, according to this aspect, it is possible to provide a technology for further improving the discharge performance of the bubbles of the supply flow path.

Aspect 8

The above-described first inclined portion **340** may be separated from a coupling portion **J1** between the supply flow path **32** and the first pressure chamber **121**. The aspect can further increase the rigidity of the wall of the supply flow path.

Aspect 9

As exemplified in FIG. 5, a range **345** from the insulating layer **141** to the first inclined portion **340** in the first direction **D1** may include an intermediate position **346** in the first direction **D1** in the multilayer substrate **30**. The aspect can also further increase the rigidity of the wall of the supply flow path.

Aspect 10

The first flow path arrangement layer **131** and the second flow path arrangement layer **132** may be made of silicon. A plane index of a front surface of the multilayer substrate **30** may be (110). A plane index of a wall surface of the first inclined portion **340** may be (111). According to this aspect, it is possible to provide the liquid ejecting head suitable for improving the discharge performance of the bubbles of the supply flow path.

Here, the plane index is also called Miller index. A surface whose plane index is (110) is also called a (110) plane. A surface whose plane index is (111) is also called a (111) plane.

Aspect 11

As exemplified in FIGS. 1 to 3, the liquid ejecting head **1** may include a sealing plate **90** bonded to the multilayer substrate **30** as a portion of the wall of the common liquid chamber **40**. In the aspect, it is possible to provide the liquid ejecting head suitable for improving the discharge performance of the bubbles of the supply flow path.

Aspect 12

As exemplified in FIGS. 1 to 3, the pressure chamber substrate **10** may include a vibration plate **16** including a portion of the wall of the first pressure chamber **121** or may include a piezoelectric element **3** disposed on the vibration plate **16**. According to this aspect, it is possible to provide the liquid ejecting head suitable for improving the discharge performance of the bubbles of the supply flow path.

Aspect 13

As exemplified in FIG. 16, a liquid ejecting apparatus **200** according to an aspect of the present technology includes the above-described liquid ejecting head **1**. In the aspect, it is possible to provide the liquid ejecting apparatus including the liquid ejecting head for improving the discharge performance of the bubbles of the supply flow path.

Here, the liquid ejecting apparatus is also referred to as a liquid discharge apparatus.

Furthermore, the present technology also has aspects such as a manufacturing method of the multilayer substrate, a manufacturing method of the liquid ejecting head, a manufacturing method of the liquid ejecting apparatus, and the like.

(2) Specific Example of Liquid Ejecting Head:

FIG. 1 schematically illustrates an ink jet type recording head as an example of the liquid ejecting head 1 in a cross section along the X direction and the Z direction. FIG. 2 is an enlarged view of the portion II in FIG. 1. FIG. 3 schematically illustrates the liquid ejecting head 1 illustrated in FIG. 1 in a cross section along the Y direction and the Z direction. Here, the X direction is a direction included in the direction along the multilayer substrate 30, directions of the pressure chamber substrate 10, the multilayer substrate 30, the nozzle plate 80, and the sealing plate 90 in the width direction, and a direction of the pressure chamber 12 in the longitudinal direction. The Y direction is a direction included in the direction along the multilayer substrate 30, directions of the pressure chamber substrate 10, the multilayer substrate 30, the nozzle plate 80, and the sealing plate 90 in the longitudinal direction, and a direction where the nozzle communication flow path 31, the nozzle 81, and the supply flow path 32 are arranged. The Z direction illustrates directions of the pressure chamber substrate 10, the multilayer substrate 30, the nozzle plate 80, and the sealing plate 90 in the thickness direction. Reference numeral D1 is a first direction from the common liquid chamber 40 of the multilayer substrate 30 toward the pressure chamber 12 of the pressure chamber substrate 10. The first direction D1 of the specific example is aligned with the Z direction.

The X direction, the Y direction, and the Z direction are orthogonal to each other, and these directions are also included in the present technology as long as these directions intersect with each other even when these directions are not orthogonal due to design or the like. The fact of "orthogonal" is not limited to strict 90°, and includes deviation from strict 90° due to error. In addition, the same in direction, position, and the like are not limited to strict matching, and includes deviation from strict matching due to error. Furthermore, the description of the positional relationship of each part is merely an example. Therefore, it is also included in the present technology to change a left-right direction to a vertical direction or a front-rear direction, to change the vertical direction to the left-right direction or the front-rear direction, to change the front-rear direction to the left-right direction or the vertical direction, and the like.

The liquid ejecting head 1 illustrated in FIG. 1 or the like is provided with the pressure chamber substrate 10, the multilayer substrate 30, a protective substrate 50, a case head 70, the nozzle plate 80, the sealing plate 90, and the like. A reservoir of the liquid ejecting head 1 includes a so-called vertical shape and includes a first common liquid chamber 40 in the multilayer substrate 30 and a second common liquid chamber 72 in the case head 70. Hereinafter, the first common liquid chamber is simply referred to as "common liquid chamber".

The pressure chamber substrate 10 has the pressure chamber 12 corresponding to each nozzle 81, an actuator 2 on a protective substrate side surface 10a, and an opening of the pressure chamber 12 on a multilayer substrate side surface 10b. The pressure chamber substrate 10 has two rows of pressure chambers in which multiple pressure chambers 12 are arranged in the Y direction which is the arrangement direction of the nozzles 81. That is, in the pressure chamber substrate 10, two pressure chambers 12 are disposed in the X direction which is the longitudinal direction of the pressure chamber 12. As matter of course, in addition to having two rows of pressure chambers, the pressure chamber substrate may have one row of pressure chamber or three or more rows of pressure chambers. The multilayer substrate side surface 10b is bonded to a pressure chamber substrate

side surface 30a of the multilayer substrate 30. The pressure chamber substrate 10 and the multilayer substrate 30 are bonded to each other by an adhesive, for example. In the present specification, the bonding and contacting includes both presence of intervening material such as an adhesive therebetween, and absence of intervening material therebetween.

For example, the pressure chamber 12 is formed in a substantially quadrangular shape elongated in a plan view as viewed from the protective substrate side surface 10a with respect to the pressure chamber substrate 10, and is disposed in the Y direction via the partition wall 12a as illustrated in FIG. 3. Each pressure chamber 12 communicates with the nozzle 81 of the nozzle plate 80 via the nozzle communication flow path 31 of the multilayer substrate 30. In the specific example, the first pressure chamber 121 means a pressure chamber selected from a plurality of pressure chambers 12 arranged in the Y direction and the second pressure chamber 122 means a pressure chamber arranged next to the first pressure chamber 121 via the partition wall 12a. The plurality of pressure chambers 12 including the first pressure chamber 121 and the second pressure chamber 122 communicate with the common liquid chamber 40 of the multilayer substrate 30.

As the material forming the pressure chamber substrate 10 except for the actuator 2, a silicon substrate, a metal such as SUS, ceramics, glass, a synthetic resin, or the like can be used. Here, SUS is an abbreviation of stainless steel. Although not particularly limited, the pressure chamber substrate 10 can be formed of a silicon monocrystalline substrate having a relatively large film thickness of, for example, approximately several hundred μm and high rigidity. The pressure chambers 12 partitioned by the plurality of partition walls 12a can be formed by anisotropic wet etching, using an alkaline solution such as KOH aqueous solution, for example.

The actuator 2 illustrated in FIGS. 1 to 3 includes the vibration plate 16 disposed on substantially the entire surface of the protective substrate side surface 10a of the pressure chamber substrate 10, and the piezoelectric element 3 disposed on the vibration plate 16. The vibration plate 16 is a wall on the side of the piezoelectric element 3 of the wall of the pressure chamber 12. Therefore, the vibration plate 16 includes a portion of the wall of the pressure chamber 12. The pressure chamber substrate side surface 30a of the multilayer substrate 30 is a wall surface of the pressure chamber 12 on the multilayer substrate 30 side.

As the material forming the vibration plate 16, a silicon oxide represented by SiO_x , a metal oxide, ceramics, a synthetic resin, or the like can be used. The vibration plate may be integrally formed with the pressure chamber substrate by modifying the front surface of the pressure chamber substrate or may be bonded to the pressure chamber substrate and laminated. Although not particularly limited, the vibration plate can be formed on the pressure chamber substrate by thermally oxidizing the silicon wafer for the pressure chamber substrate with a diffusion furnace at approximately 1000° C. to 1200° C. In addition, the vibration plate may have a laminated structure such as a structure in which a zirconium oxide layer is laminated on a silicon oxide layer.

The piezoelectric element 3 illustrated in FIGS. 2 and 3 includes a first electrode 21 formed on the vibration plate 16, a piezoelectric layer 23 formed on the first electrode 21, and a second electrode 22 formed on the piezoelectric layer 23. One of the electrodes 21 and 22 may be a common electrode arranged in a range corresponding to the plurality of pres-

sure chambers 12. In FIG. 1, it is illustrated that the first electrode 21 is coupled, as an individual electrode, to a coupling wiring 66 such as a flexible substrate. As the material forming the electrodes and 22, one or more materials such as platinum represented by Pt, gold represented by Au, iridium represented by Ir, titanium represented by Ti, and conductive oxides of these metals can be used. The thickness of the electrodes 21 and 22 is not particularly limited, and can be set to approximately several nm to several hundred nm. A lead electrode made of a conductive material such as a metal may be coupled to at least one of the electrodes 21 and 22. As the piezoelectric layer 23, a ferroelectric material such as a lead-based perovskite oxide such as PZT, a non-lead perovskite oxide, or the like can be used. Here, PZT is an abbreviation for lead zirconate titanate, and is $Pb(Zr_xTi_{1-x})O_3$ in stoichiometric ratio. The thickness of the piezoelectric layer 23 is not particularly limited, and can be set to approximately several hundred nm to several μm .

The electrodes 21 and 22 and the lead electrode can be formed by, for example, forming and patterning an electrode film on a vibration plate by a vapor phase method such as a sputtering method. The piezoelectric layer 23 can be formed by, for example, baking and patterning a piezoelectric precursor film formed on the first electrode by a liquid phase method such as a spin coating method or a gas phase method.

A driving element for moving the liquid from the pressure chamber to the nozzle is not limited to the above-described piezoelectric element 3, and a heating element or the like for generating a bubble in the pressure chamber by heat generation may be used. Therefore, the actuator 2 is not limited to the piezoelectric actuator including the piezoelectric element and the vibration plate, and may be an actuator including a heating element that transmits heat to the pressure chamber.

The multilayer substrate 30 illustrated in FIGS. 1 to 3 has a liquid flow path including the common liquid chamber 40, an inflow flow path 38 coupled to the common liquid chamber 40 from the second common liquid chamber 72 of the case head 70, the supply flow path 32 coupled to the pressure chamber 12 from the common liquid chamber 40, and the nozzle communication flow path 31 coupled to the nozzle of the nozzle plate 80 from the pressure chamber 12. Since the multilayer substrate 30 has the above-described liquid flow path, the multilayer substrate 30 is also called a flow path substrate. The pressure chamber substrate 10 and the case head 70 are bonded to the pressure chamber substrate side surface 30a of the multilayer substrate 30. The multilayer substrate 30 and the case head 70 are bonded to each other by an adhesive, for example. The nozzle plate and the sealing plate 90 are bonded to a nozzle plate side surface 30b of the multilayer substrate 30. The multilayer substrate 30 and the nozzle plate 80 are bonded to each other by an adhesive, for example. The multilayer substrate 30 and the sealing plate 90 are bonded to each other by an adhesive, for example.

As illustrated in FIGS. 2 and 3, the multilayer substrate 30 of the specific example includes the first flow path arrangement layer 131, the insulating layer 141, and the second flow path arrangement layer 132 in order from the nozzle plate 80 side. The multilayer substrate 30 has the common liquid chamber 40 on the side of the first flow path arrangement layer 131 from the position of the insulating layer 141, and includes the liquid chamber wall portion 33 on the side of the second flow path arrangement layer 132 from the position of the insulating layer 141. The first wall surface 33a

facing the common liquid chamber 40 in the liquid chamber wall portion 33 is aligned with the surface of the second flow path arrangement layer 132 on the side of the insulating layer 141. The sealing plate 90 is a portion of the wall of the common liquid chamber 40. The multilayer substrate 30 has two common liquid chambers 40 as illustrated in FIG. 1. Each common liquid chamber 40 is arranged on the multilayer substrate 30 corresponding to the pressure chamber row.

The common liquid chamber 40 stores liquid Q1 such as ink. The inflow flow path 38 has a hole shape penetrating in the Z direction with respect to the second flow path arrangement layer 132 and allows the liquid Q1 to pass from the second common liquid chamber 72 of the case head 70 to the common liquid chamber 40. An inlet port 42, which is an outlet portion of the inflow flow path 38, is an opening portion of the inflow flow path 38 formed in the common liquid chamber 40. The position of the inflow port is aligned with the surface of the second flow path arrangement layer 132 on the side of the insulating layer 141. The supply flow path 32 has a hole shape penetrating in the Z direction with respect to the second flow path arrangement layer 132, and is an individual flow path arranged for each pressure chamber 12. Therefore, the liquid flow path branches from the common liquid chamber 40 into a plurality of supply flow paths 32. Each supply flow path 32 passes the liquid Q1 from the common liquid chamber 40 to the corresponding pressure chamber 12. A supply port 44 which is an inlet portion of the supply flow path 32 is an opening portion of the supply flow path 32 formed in the common liquid chamber 40, and is coupled to the first wall surface 33a of the liquid chamber wall portion 33 and the insulating layer 141. The plurality of supply ports 44 in each common liquid chamber 40 are arranged in the Y direction which is the arrangement direction of the pressure chambers 12. The position of each supply ports 44 is aligned with the surface of the second flow path arrangement layer 132 on side of the insulating layer 141. The nozzle communication flow path 31 has a hole shape that penetrates the entire multilayer substrate 30 in the first direction D1 which is the Z direction, and is an individual flow path arranged for each pressure chamber 12. Therefore, the nozzle communication flow path 31 has a hole shape that penetrates the first flow path arrangement layer 131, the insulating layer 141, and the second flow path arrangement layer 132. Each nozzle communication flow path 31 passes the liquid Q1 from the pressure chamber 12 to the nozzle 81. The multilayer substrate 30 has two rows of nozzle communication flow paths 31 aligned with the pressure chamber rows. In each row of the nozzle communication flow path 31, as illustrated in FIG. 3, the nozzle communication flow paths 31 may be linearly arranged in the Y direction, or the nozzle communication flow paths 31 may be arranged in a zigzag manner.

As will be described in detail later, projection portions 300 are arranged in the inlet portion coupled to the first wall surface 33a and the insulating layer 141 in the supply flow path 32. In this specific example, projection portions 300 are also arranged in the nozzle communication flow path 31.

As the materials forming the first flow path arrangement layer 131 and the second flow path arrangement layer 132, semiconductors such as silicon represented by Si, metals, ceramics, and the like can be used. As the material forming the insulating layer 141, silicon oxide, metal oxide, ceramics, synthetic resin, or the like can be used. Although not particularly limited, when an SOI substrate is used for the multilayer substrate 30, the first flow path arrangement layer 131 and the second flow path arrangement layer 132 are

11

made of silicon and the insulating layer 141 is made of silicon oxide. As the SOI substrate, for example, it is possible to use a multilayer substrate in which the first flow path arrangement layer 131 and the second flow path arrangement layer 132 are silicon single crystal substrates and whose surface is the (110) plane.

The liquid flow path of the multilayer substrate 30 can be formed by, for example, anisotropic wet etching using an alkaline solution such as KOH aqueous solution or the like.

As illustrated in FIGS. 1 and 2, the protective substrate 50 of the specific example has a space 52 that does not interfere with the movement of the piezoelectric element 3 in a region facing the piezoelectric element 3, and is bonded onto the pressure chamber substrate 10 including the piezoelectric element 3. The protective substrate 50 and the pressure chamber substrate 10 are bonded to each other with an adhesive, for example. Since the protective substrate 50 covers the actuator 2, the actuator 2 is protected from intrusion of liquid or the like. As a material forming the protective substrate 50, a semiconductor such as silicon, a metal such as stainless steel, ceramics, glass, a synthetic resin, or the like can be used. Although not particularly limited, the protective substrate 50 can be formed of a silicon monocrystalline substrate having a relatively large film thickness of, for example, approximately several hundred μm and high rigidity.

When the actuator 2 is protected by the case head or the like, it is possible to omit the protective substrate 50 from the liquid ejecting head 1.

As illustrated in FIGS. 1 and 2, the case head 70 of the specific example has the second common liquid chamber that stores liquid Q1 to be supplied to each common liquid chamber 40, and to the pressure chamber row. The case head 70 has a space forming portion 71 located in a region facing the protective substrate 50, a gap 74 through which the coupling wiring 66 passes, and the like, and is bonded to the pressure chamber substrate side surface 30a of the multilayer substrate 30. The case head 70 and the multilayer substrate 30 are bonded to each other with an adhesive, for example. The space forming portion 71 has a space into which the protective substrate 50 is received. The second common liquid chamber 72 stores the liquid Q1 flowing in from a liquid introduction portion 73. The pressure chamber substrate side surface 30a of the multilayer substrate 30 is a portion of the wall surface of the pressure chamber 12 and also is a portion of the wall surface of the second common liquid chamber 72. As the material forming the case head 70, a metal such as glass, ceramics, stainless steel, a synthetic resin, a semiconductor such as silicon, or the like can be used.

A drive circuit 65 illustrated in FIG. 1 drives the piezoelectric element 3 via the coupling wiring 66 electrically coupled to the electrodes 21 and 22. For the drive circuit 65, a circuit board, an IC, or the like can be used. Here, IC is an abbreviation for integrated circuits. Although not illustrated, the coupling wiring 66 is coupled to a control device of the liquid ejecting apparatus, and the drive circuit 65 is controlled by the control device via the coupling wiring 66 to drive the piezoelectric element 3. For the coupling wiring 66 including the drive circuit 65, FPC, COF, or the like can be used. Here, FPC is an abbreviation for "flexible printed circuit". COF is an abbreviation for "chip on film".

As illustrated in FIGS. 1 to 3, the nozzle plate 80 of the specific example has a plurality of nozzles 81 penetrating in the Z direction and is bonded to the nozzle plate side surface 30b of the multilayer substrate 30. The nozzle plate 80 and the multilayer substrate 30 are bonded to each other with an

12

adhesive, for example. The nozzle 81 is an opening portion formed in the flat plate-like nozzle plate 80 and penetrates in the Z direction. The nozzle plate 80 has two rows of nozzles 81 aligned with the pressure chamber row. In each row of the nozzles 81, as illustrated in FIG. 3, the nozzles 81 may be linearly arranged in the Y direction, or the nozzles 81 may be arranged in a zigzag manner. A surface of the nozzle plate on a side opposite to the surface bonded to the multilayer substrate 30 is a nozzle surface 80b from which the droplet Q0 is discharged. A negative pressure is applied to the nozzle surface 80b at the time of cleaning.

As the material forming the nozzle plate 80, a metal such as stainless steel, a semiconductor such as glass, ceramics, synthetic resin, silicon, or the like can be used. Although not particularly limited, the nozzle plate 80 can be formed of glass ceramics having a thickness of, for example, approximately 0.01 to 1 mm.

The sealing plate 90 illustrated in FIGS. 1 and 2 is a flexible film and functions as a vibration absorbing body that absorbs pressure fluctuations of the liquid Q1 in the common liquid chamber 40. Since the sealing plate 90 has a compliance function, the sealing plate 90 is also called a compliance sheet. The sealing plate 90 sealing each common liquid chamber 40 is bonded to the nozzle plate side surface 30b of the multilayer substrate 30 as a portion of the wall of the common liquid chamber 40. The sealing plate 90 and the multilayer substrate 30 are bonded to each other with an adhesive, for example. In addition to sealing the common liquid chamber 40 with the sealing plate 90 for each common liquid chamber 40, a plurality of common liquid chambers 40 may be collectively sealed with one sealing plate to seal the common liquid chamber 40. In addition, instead of the sealing plate 90, the common liquid chamber 40 may be sealed by the nozzle plate 80. As a material forming the common liquid chamber 40, a synthetic resin, a semiconductor such as silicon, a metal such as stainless steel, or the like can be used.

In the liquid ejecting head 1 having the above-described structure, the liquid Q1 sequentially passes through the liquid introduction portion 73, the second common liquid chamber 72, the inflow flow path 38, the common liquid chamber 40, the supply flow path 32, the pressure chamber 12, and the nozzle communication flow path 31, and is ejected as a droplet Q0 from the nozzle 81 by the operation of the actuator 2. Here, the liquid introduction portion 73, the second common liquid chamber 72, the inflow flow path 38, and the common liquid chamber 40 are common flow paths for the plurality of pressure chambers 12. The supply flow path 32, the pressure chamber 12, the nozzle communication flow path 31, and the nozzle 81 are individual flow paths corresponding to each pressure chambers 12. Therefore, the liquid Q1 in the common liquid chamber 40 is divided into individual supply flow paths 32 and flows out. When the drive circuit 65 applies a voltage between the first electrode 21 and the second electrode 22 to bend the actuator 2 toward the pressure chamber 12 side, the liquid Q1 in the pressure chamber 12 flows to the nozzle 81 via the nozzle communication flow path 31. As a result, the droplet Q0 is ejected from the nozzle 81. In addition, when the drive circuit 65 stops applying the above-described voltage, the actuator 2 moves to the side opposite to the pressure chamber 12, so that the liquid Q1 in the common liquid chamber 40 flows into the pressure chamber 12 via the supply flow path 32. Therefore, the actuator 2 can repeatedly eject the droplet Q0 from the nozzle 81.

When a plurality of droplets Q0 ejected by the liquid ejecting head 1 land on a print substrate, dots of the plurality

of droplets Q0 are formed on the print substrate, and a printing image of a plurality of dots is expressed on the print substrate. Here, the print substrate is a material that holds a printed image, and has various two-dimensional shapes such as a polygon and a circle, and various three-dimensional shapes such as prismatic and spherical. As the material forming the print substrate, paper, synthetic resin, metal, ceramics, and the like can be used. Dots are the smallest unit of recording results formed by the liquid droplets on the print substrate. In order to increase the resolution of the printed image, it is necessary to make the nozzle pitch finer, for example, 300 dpi or more. In order to make the nozzle pitch finer, it is necessary to narrow the interval between the adjacent nozzles 81, and it is necessary to narrow the interval between the adjacent supply flow paths 32.

FIGS. 23A to 23C schematically illustrate the manufacturing step of the liquid ejecting head according to the comparative example. The substrate 901 being processed illustrated in FIGS. 23A to 23C finally becomes a flow path substrate having the common liquid chamber 940, the supply flow path 932, and the like. A silicon single crystal substrate in which the pressure chamber substrate side surface 30a and the nozzle plate side surface 30b are the (110) plane is used as a base substrate for forming the flow path substrate. In FIGS. 23A to 23C, the nozzle communication flow paths and the like are not illustrated.

First, in a thermal oxidation step ST91, a treatment of thermally oxidizing the surface of the base substrate at 1000° C. to 1200° C. is performed. By this treatment, as illustrated in FIG. 23A, a hard mask film 951 made of silicon oxide is formed on both surfaces of a flow path arrangement layer 931 made of silicon.

Next, in a through-hole forming step ST92, a portion of the hard mask film 951 corresponding to a supply flow path corresponding region 932a and an inflow flow path corresponding region 938a is removed, and an anisotropic wet etching is performed with an alkaline aqueous solution. By this treatment, as illustrated in FIG. 23B, through-holes are formed in the supply flow path corresponding region 932a, the inflow flow path corresponding region 938a, and the like.

Next, in a common liquid chamber forming step ST93, a portion of the hard mask film 951 corresponding to a common liquid chamber corresponding region 940a of the nozzle plate side surface 30b is removed and an anisotropic wet etching is performed with an alkaline aqueous solution. By this treatment, as illustrated in FIG. 23C, the common liquid chamber 940 is formed on the nozzle plate side surface 30b side in the common liquid chamber corresponding region 940a of the flow path arrangement layer 931, and the liquid chamber wall portion 933 are formed on the pressure chamber substrate side surface 30a side.

When anisotropic wet etching is performed around the through-hole after forming the through-hole, the wall in the vicinity of the opening of the through-hole is obliquely etched. Therefore, the wall surface of the inlet portion from the common liquid chamber 940 toward the supply flow path 932 has a sagging shape 932b which is lowered to the supply flow path 932 side. In addition, a sagging shape 932c which is lowered to the supply flow path 932 side is formed also in the partition wall between the supply flow paths 932. Here, the depth of the sagging shape of the supply flow path 932 is set to a depth deeper among the depth of the sagging shape 932b and the depth of the sagging shape 932c.

The depth of sagging shape of the supply flow path 932 varies depending on anisotropic wet etching time, temperature and alkali concentration of the etchant, impurities

contained in the etchant, and the like. Therefore, it is difficult to make the depth of the sagging shape of the supply flow path 932 constant. Such a problem is more conspicuous when narrowing the interval between the adjacent supply flow paths 32 in order to increase the resolution of the printed image.

When the depth of the sagging shape varies, the supply side inertance varies, which is the inertance of the liquid flow path on the side supplying the liquid to the pressure chamber. When the supply side inertance varies, it is difficult to control the weight of the liquid droplet ejected from the nozzle.

Inertance is a parameter representing fluid movement difficulty. When the liquid ejecting head has the vibration plate, the amount of liquid movement with respect to volume change of the vibration plate is determined by inertance.

In general, inertance is defined by the following equation.

$$M = \rho L/S \quad (1)$$

Where, M represents inertance, ρ represents the density of the fluid, L represents the length of the flow path, and S represents the cross-sectional area of the flow path.

According to Equation (1), as the liquid flow path is narrowed, the inertance M increases and the liquid is unlikely to flow. As the liquid flow path is longer, the inertance M increases and the liquid is unlikely to flow.

The weight of the liquid droplet from the nozzle is determined by the volume change amount of the vibration plate and the following discharge efficiency.

$$E = M_s / (M_n + M_s) \quad (2)$$

Where, E represents the discharge efficiency, M_s represents the supply side inertance, and M_n represents the nozzle side inertance which is the inertance of the liquid flow path on the side from which the liquid is sent from the pressure chamber to the nozzle.

According to Equation (2), for example, when the nozzle side inertance M_n decreases by expanding the liquid flow path on the nozzle side, the discharge efficiency E increases, and when the supply side inertance M_s increases by narrowing the liquid flow path on the supply side, the discharge efficiency E increases.

When a liquid droplet is ejected from the nozzle, the liquid corresponding to the liquid droplet is supplied to the pressure chamber. Delay in supply of the liquid to the pressure chamber may occur due to the flow path resistance of the liquid flow path on the supply side. When the flow path resistance of the liquid flow path on the supply side is large and the liquid droplet is repeatedly ejected from the nozzle, the supply of the liquid to the pressure chamber cannot be made in time, and the weight of the liquid droplet ejected from the nozzle is small. When the cross-sectional area of the liquid flow path on the supply side is made small in order to increase the supply side inertance M_s , the flow path resistance of the liquid flow path on the supply side increases, so that there is a possibility that the above-described weight reduction occurs. When the cross-sectional area of the liquid flow path on the supply side is increased, although the flow path resistance of the liquid flow path on the supply side is decreased, there is a possibility that the discharge performance of the bubbles may decrease due to a decrease in the flow speed of the liquid. Therefore, in order to achieve both high supply side inertance M_s and good discharge performance of the bubbles, it is preferable to keep constant the shape of the liquid flow path on the supply side.

In the specific example, by using the insulating layer 141 of the multilayer substrate 30, the sagging shape of the supply flow path 32 is suppressed, and variations in supply side inertance are reduced. In addition, by allowing the inlet portion of the supply flow path 32 to be narrower than the other portions, the bubble attached to the wall surface of the inlet portion of the supply flow path 32 is likely to be discharged at the time of cleaning.

When bonding a substrate having a supply flow path which has not sagging shaped to a substrate having a common liquid chamber with an adhesive, it is required to bond these substrates so that the mass of adhesive does not get mixed in the liquid flow path, and a treatment for managing the accuracy of the bonding position is required. As the number of manufacturing steps for that purpose increases, the manufacturing cost increases, and it is also expected to increase the cost because the yield of the substrate decreases to ensure the accuracy of the bonding position.

(3) Description of Supply Flow Path According to Specific Example:

FIG. 4 schematically illustrates the multilayer substrate 30 as viewed from the pressure chamber substrate 10. In FIG. 4, the positions of the pressure chambers 12 are indicated by two-dot chain lines. FIG. 5 schematically illustrates the first cross section SC1 of the multilayer substrate 30 at a position of V-V in FIG. 4. FIG. 6A schematically illustrates the second cross section SC2 of the supply flow path 32 at a position of VIA-VIA in FIG. 5. FIG. 6B schematically illustrates an example of a third cross section SC3 of the supply flow path 32 at a position of VIB-VIB in FIG. 5.

Here, Reference numeral D2 is a second direction that intersects with the first direction D1. The second direction D2 of the specific example is a direction included in the direction along the multilayer substrate 30, a direction passing through two projection portions 300 which face each other in a plan view as illustrated in FIG. 4, and is orthogonal to the first direction D1. The first cross section SC1 is a longitudinal cross section along the first direction D1 and the second direction D2. The second cross section SC2 and the third cross section SC3 are cross sections orthogonal to the first direction D1.

In a plan view illustrated in FIG. 4, the shape of each nozzle communication flow path 31 and each supply flow path 32 is substantially parallelogram. In each of the nozzle communication flow paths 31 and the supply flow paths 32, two projection portions 300 facing each other are formed. In the specific example, the two projection portions 300 arranged in the supply flow path 32 will be described in detail.

As illustrated in FIG. 5, the common liquid chamber 40 is disposed in the first flow path arrangement layer 131 and the insulating layer 141, and the supply flow path 32 has a hole shape penetrating in the first direction D1 with respect to the second flow path arrangement layer 132. The liquid chamber wall portion 33 disposed in the second flow path arrangement layer 132 is a portion of the wall of the supply flow path 32. In the first cross section SC1, the supply flow path 32 includes the first portion 310 having the first width W1 and the second portion 320 having the second width W2. The first width W1 of the first portion 310 is narrower than the second width W2 of the second portion 320.

The first portion 310 includes the first facing portion 311 protruding toward the inside of the supply flow path 32 from the second portion 320 in a facing wall portion facing the liquid chamber wall portion 33 across the supply flow path

32. The first facing portion 311 is at a position including the insulating layer 141 in the facing wall portion 34. In addition, the first portion 310 includes the second facing portion 312 protruding toward the inside of the supply flow path 32 from the second portion 320 in the liquid chamber wall portion 33. The second facing portion 312 is at a position facing the first facing portion 311.

The supply flow path 32 includes the first inclined portion 340 having the second wall surface 341 inclined with respect to the first direction D1 between the first facing portion 311 and the second portion 320. The first inclined portion 340 has an inclination inside the supply flow path as the first inclined portion 340 approaches the first facing portion 311. In addition, the supply flow path 32 includes the second inclined portion 350 having the third wall surface 351 inclined with respect to the first direction D1 between the second facing portion 312 and the second portion 320. The second inclined portion 350 has an inclination inside the supply flow path 32 as the second inclined portion 350 approaches the second facing portion 312. In the specific example, the pressure chamber substrate side surface 30a, which is the front surface of the second flow path arrangement layer 132 made of silicon single crystal, is a (110) plane and both the second wall surface 341 and the third wall surface 351 are (111) planes. The first inclined portion 340 is separated from the coupling portion J1 between the supply flow path 32 and the pressure chamber 12 and the second portion 320 is provided between the first inclined portion 340 and the coupling portion J1. The second inclined portion 350 is separated from the coupling portion J1 between the supply flow path 32 and the pressure chamber 12 and the second portion 320 is provided between the second inclined portion 350 and the coupling portion J1.

The range 345 from the insulating layer 141 to the first inclined portion 340 in the supply flow path 32 includes the intermediate position 346 in the first direction D1 in the multilayer substrate 30. In the example illustrated in FIG. 5, the range of the insulating layer 141 includes the intermediate position 346 in the multilayer substrate 30. As matter of course, the range of the first inclined portion 340 may include the intermediate position 346 in the multilayer substrate 30.

As described above, the combination of the first inclined portion 340 and the first facing portion 311 and the combination of the second inclined portion 350 and the second facing portion 312 constitute the projection portion 300 protruding from the second portion 320 to the inside of the supply flow path 32. As described above, the range of the projection portion 300 in the first direction D1 in the multilayer substrate 30 includes the intermediate position 346 in the first direction D1 in the multilayer substrate 30.

An extension wall portion 35 arranged in the direction D3 opposite to the first direction D1 from the facing wall portion 34 is a portion of the wall of the common liquid chamber 40. The extension wall portion 35 illustrated in FIG. 5 includes a third inclined portion 360 having a fourth wall surface 361 inclined with respect to the first direction D1 between the first facing portion 311 and a third portion 330. The third inclined portion 360 has an inclination inside the common liquid chamber 40 as the third inclined portion 360 approaches the first facing portion 311. In the specific example, the nozzle plate side surface 30b, which is the front surface of the first flow path arrangement layer 131 made of silicon single crystal, is a (110) plane and the fourth wall surface 361 is a (111) plane. Although not illustrated in FIG. 5, the range from the insulating layer 141 to the third inclined portion 360 in the multilayer substrate 30 includes

the intermediate position 346 in the first direction D1 in the multilayer substrate 30. The range of the third inclined portion 360 may include the intermediate position 346 in the multilayer substrate 30.

As illustrated in FIG. 5, the first wall surface 33a and the second facing portion 312 of the liquid chamber wall portion 33 are aligned with the position of the insulating layer 141 in the first direction D1. As a result, the wall surface of the inlet portion of the supply flow path 32 has not sagging shaped and has the first width W1 narrower than the second width W2 of the second portion 320 of the first cross section SC1 along the first direction D1 and the second direction D2. Since the sagging shape, which is a factor that the supply side inertance varies, is not formed in the supply flow path 32, variations in the supply side inertance are reduced, and as a result, the weight variation of the liquid droplet Q0 from the nozzle 81 is suppressed.

In addition, since the second width W2 of the second portion 320 of the supply flow path 32 is wider than the first width W1 of the first portion 310 in the inlet portion, the flow path resistance of the supply flow path 32 does not excessively increase and the weight of the liquid droplet Q0 is suppressed from decreasing even when the liquid droplet now abandoned Q0 is repeatedly ejected from the nozzle 81.

As illustrated in FIG. 6A, the second cross section SC2 of the second portion 320 of the supply flow path 32 is a substantially parallelogram. The shape of the second portion 320 in the second cross section SC2 has the first angle AN1 and the second angle AN2 facing the first angle AN1. The first angle AN1 and the second angle AN2 constitute a diagonal in the parallelogram. When θ is the internal angle of the first angle AN1 and the second angle AN2, $0^\circ < \theta < 90^\circ$, and preferably $45^\circ < \theta < 90^\circ$. Therefore, the first angle AN1 and the second angle AN2 are acute angles.

As illustrated in FIG. 5, there are two projection portions 300 in the supply flow path 32. The projection portion 300 including the first inclined portion 340 is disposed in a direction D3 opposite to the first direction D1 from the first angle AN1. The projection portion 300 including the second inclined portion 350 is disposed in a direction D3 opposite to the first direction D1 from the second angle AN2. Therefore, as illustrated in FIG. 6B, the third section SC3 of the first portion 310 of the supply flow path 32 has a substantially hexagonal shape such that the diagonal of an acute angle is cut off from the parallelogram.

When the bubble remains in the supply flow path 32 as described above, the bubble affects the ejection of the liquid droplet Q0, so that a treatment of removing the bubble from the liquid flow path is performed by a cleaning device (not illustrated). The cleaning device has a cap that covers the nozzle surface 80b, sucks air in the cap, and applies a negative pressure of, for example, approximately -20 kPa to -60 kPa to the nozzle surface 80b to forcibly suck the liquid Q1 from the nozzle 81. As a result, the flow of the liquid Q1 in the first direction D1 occurs in the supply flow path 32.

In this specific example, since there are the first inclined portion 340 and the second inclined portion 350 that gradually expand from the narrow first portion 310 toward the second portion 320 in the supply flow path 32, the liquid Q1 is unlikely to stagnate between the first portion 310 and the second portion 320 when the liquid Q1 flows in the supply flow path 32 in the first direction D1 at the time of cleaning or the like. In particular, the first angle AN1 and the second angle AN2 are acute angles, and the flow of the liquid Q1 is likely to be slow in the vicinity of these angles AN1 and AN2. The first inclined portion 340 is disposed in the direction D3 opposite to the first direction D1 from the first

angle AN1, and the second inclined portion 350 is disposed in the direction D3 opposite to the first direction D1 from the second angle AN2. Therefore, stagnation of the liquid Q1 is effectively suppressed, the flow of the liquid Q1 is improved, and the bubble is likely to flow out. Therefore, the residual bubbles in the supply flow path 32 are suppressed.

In addition, as illustrated in FIG. 6B, the third cross section SC3 of the first portion 310 which is the inlet portion of the supply flow path 32 has a substantially hexagonal shape and is nearly circular in shape as compared with the substantially parallelogram. In FIG. 6B, bubbles 800 adhering to the inlet portion of the supply flow path 32 are illustrated by two-dot chain lines. When the cross section of the inlet portion of the supply flow path is substantially parallelogram and the bubbles adhere to the wall surface of the inlet portion of the supply flow path, the liquid flows through the acute angle portion of the substantially parallelogram which is the side of the bubbles at the time of cleaning, so that there is a possibility that the bubbles are unlikely to be discharged. As illustrated in FIG. 6B, when the cross section of the inlet portion of the supply flow path 32 has a substantially hexagonal shape, the above-described flow of the liquid is suppressed, so that the bubbles 800 are easily discharged from the inlet portion of the supply flow path 32 at the time of cleaning.

Furthermore, since there is the third inclined portion 360 that gradually extends toward the inside of the common liquid chamber 40 from the third portion 330 toward the first portion 310 on the extension wall portion 35 of the common liquid chamber 40. Therefore, when the liquid Q1 flows from the common liquid chamber 40 to the supply flow path 32 at the time of cleaning or the like, the flow improves and the bubbles are guided by the third inclined portion 360 and are likely to get over the first portion 310. Therefore, the bubbles remaining in the inlet portion of the supply flow path 32 are suppressed.

As described above, in the specific example, it is possible to reduce the variation of the supply side inertance, to suppress the weight variation of the liquid droplet Q0 from the nozzle 81, to suppress the decrease in the weight of the liquid droplet Q0 when repeatedly ejecting the liquid droplet Q0 from the nozzle 81, and to improve the discharge performance of the bubbles in the supply flow path.

(4) Specific Example of Manufacturing Method of Liquid Ejecting Head:

Next, with reference to FIGS. 7A to 7C, 8A to 8C, 9A to 9C, 10A and 10B, and the like, a manufacturing method of the liquid ejecting head 1 will be exemplified. FIGS. 7A to 7C, 8A to 8C, 9A to 9C, 10A and 10B schematically illustrate a forming method of the multilayer substrate 30 having the liquid flow path. For the sake of convenience, a cross section of the substrate is illustrated at a position passing through the projection portion 300 in a positional relationship in which the multilayer substrate 30 illustrated in FIG. 2 is turned upside down. For the sake of clarity, elements appearing behind are omitted, and the ratio of the thickness of each layer may be different from the actual ratio.

FIG. 7A illustrates a cross section of a base substrate 100 for forming the multilayer substrate 30 having the liquid flow path. The base substrate 100 illustrated in FIG. 7A is an SOI substrate, the first flow path arrangement layer 131 and the second flow path arrangement layer 132 are made of silicon, and the insulating layer 141 is made of silicon oxide. The nozzle plate side surface 30b which is the front surface of the first flow path arrangement layer 131 is a (110) plane, and the pressure chamber substrate side surface 30a which

is the front surface of the second flow path arrangement layer **132** is also a (110) plane. Thicknesses of the first flow path arrangement layer **131** and the second flow path arrangement layer **132** are not particularly limited, and can be set to approximately 100 to 400 μm . The thickness of the insulating layer **141** is not particularly limited, and can be set to approximately 0.4 to 2 μm .

First, in a hard mask forming step ST1, a treatment is performed of forming a hard mask film **151** on the entire surface of the pressure chamber substrate side surface **30a** and the nozzle plate side surface **30b**, which are the front surfaces of the base substrate **100**. FIG. 7B illustrates a state where the hard mask film **151** is formed on the substrate **101** being processed. The thickness of the hard mask film **151** is not particularly limited, and can be set to approximately 50 nm to 2 μm . As the material forming the hard mask film **151**, silicon oxide, silicon nitride, metal oxide, ceramics, synthetic resin, or the like can be adopted. Silicon nitride is expressed as Si_3N_4 in stoichiometric ratio. Although not particularly limited, when the base substrate **100** is an SOI substrate, and the base substrate **100** is thermally oxidized in a diffusion furnace at approximately 1000°C. to 1200°C., the hard mask film **151** made of silicon oxide can be integrally formed on the front surface of the base substrate **100**. In addition, when the hard mask film **151** is formed of silicon nitride, the hard mask film **151** can be formed by reactive sputtering or the like.

Next, in a first patterning step ST2, as illustrated in FIG. 7C, a treatment is performed of removing the hard mask films in the nozzle communication flow path corresponding region **151a** corresponding to the nozzle communication flow path **31**, a supply flow path corresponding region **151b** corresponding to the supply flow path **32**, and an inflow flow path corresponding region **151c** corresponding to the inflow flow path **38** in the hard mask film **151**. The first patterning step ST2 may include a first photoresist forming step, a first photoresist patterning step, a first hard mask removing step, and a first photoresist removing step. In the first photoresist forming step, a treatment is performed of applying a photoresist on the hard mask film **151**. In the first photoresist patterning step, a treatment is performed of removing photoresist in the nozzle communication flow path corresponding region **151a**, the supply flow path corresponding region **151b**, and the inflow flow path corresponding region **151c** of the photoresist by exposure or the like. In the first hard mask removing step, a treatment is performed of removing the portion of the hard mask film **151** not covered with the photoresist by wet etching, using an etchant for removing a portion of the hard mask film **151**. As an etchant for this treatment, an aqueous hydrogen fluoride solution, a mixed solution of hydrogen fluoride and ammonium fluoride, or the like can be used. In the first photoresist removing step, a treatment is performed of removing the first photoresist remaining on the hard mask film **151** with a solvent or the like.

Next, in the second patterning step ST3, as illustrated in FIG. 8A, a treatment is performed of thinning the hard mask film in the common liquid chamber corresponding region **151d** corresponding to the common liquid chamber **40** in the hard mask film **151**. The second patterning step ST3 may include a second photoresist forming step, a second photoresist patterning step, a second hard mask removing step, and a second photoresist removing step. In the second photoresist forming step, a treatment is performed of applying photoresist on both surfaces of the substrate **101** being processed. In the second photoresist patterning step, a treatment is performed of removing the photoresist in the common liquid chamber corresponding region **151d** of the hard mask film **151** with a solvent or the like.

mon liquid chamber corresponding region **151d** of the photoresist by exposure or the like. In the second hard mask removing step, a treatment is performed of thinning the hard mask film **151** in a portion not covered with the photoresist by wet etching, using an etchant for removing a portion of the hard mask film **151**. The thickness of the hard mask film **151** to be left can be decreased by lengthening the wet etching time, and the thickness can be increased by shortening the wet etching time. For the etchant of this treatment, an aqueous solution of hydrogen fluoride, a mixed solution of hydrogen fluoride and ammonium fluoride, or the like can be used. In the second photoresist removal step, a treatment is performed of removing the second photoresist remaining on both surfaces of the substrate **101** being processed with a solvent or the like.

Next, in an ICP mask forming step ST4, as illustrated in FIG. 8B, a treatment is performed of disposing a third photoresist **153** on a portion of the pressure chamber substrate side surface **30a** and the nozzle plate side surface **30b** which are the front surfaces of the substrate **101** being processed, except for a plurality of prepared holes. Here, ICP is an abbreviation for inductively coupled plasma. As illustrated in FIG. 8C, the plurality of prepared holes include a plurality of first prepared holes **153a** on the side of the nozzle plate side surface **30b** and a plurality of second prepared holes **153b** on the side of the pressure chamber substrate side surface **30a**. The plurality of first prepared holes **153a** are arranged in the nozzle communication flow path corresponding region **151a** and the supply flow path corresponding region **151b**. The plurality of second prepared holes **153b** are also arranged in the nozzle communication flow path corresponding region **151a** and the supply flow path corresponding region **151b**.

The ICP mask forming step ST4 may include a third photoresist forming step and a third photoresist patterning step. In the third photoresist forming step, a treatment is performed of applying photoresist on both surfaces of the substrate **101** being processed. In the third photoresist patterning step, a treatment is performed of removing the third photoresist in regions corresponding to the first prepared hole **153a** and the second prepared hole **153b** in the photoresist by exposure or the like.

Next, in a prepared hole formation step ST5, as illustrated in FIG. 8C, a treatment is performed of forming the first prepared hole **153a** and the second prepared hole **153b** reaching the insulating layer **141** from both surfaces of the substrate **101** being processed. The first prepared hole **153a** and the second prepared hole **153b** in the nozzle communication flow path corresponding region **151a** are thinner than those of the nozzle communication flow path **31**. The first prepared hole **153a** and the second prepared hole **153b** in the supply flow path corresponding region **151b** are thinner than those of the supply flow path **32**.

For forming the first prepared hole **153a** and the second prepared hole **153b**, ICP, laser, or the like can be used. In an etching apparatus using ICP, a material to be etched is processed by etching using plasma. When the material to be etched is silicon, gases such as tetrafluoromethane represented by the molecular formula CF_4 , trifluoromethane represented by the molecular formula CHF_3 , and the like can be used as the etchant. Although not particularly limited, when forming the first prepared hole **153a**, and ICP treatment is performed on the side of the nozzle plate side surface **30b**, it is possible to form the first prepared holes **153a** reaching the insulating layer **141** with respect to the first flow path arrangement layer **131**. When forming the second prepared hole **153b**, and ICP treatment is performed on the

side of the pressure chamber substrate side surface 30a, it is possible to form the second prepared hole 153b reaching the insulating layer 141 with respect to the second flow path arrangement layer 132. In the treatment of ICP, the insulating layer 141 remains without being etched. For forming the first prepared hole 153a and the second prepared hole 153b, a laser may be used in combination with ICP.

When performing anisotropic wet etching on silicon crystals, the etching rate of the (111) plane is lower than that of the (110) plane and the (100) plane, and etching is difficult. The front surface of the side wall in the first prepared hole 153a and the front surface of the side wall in the second prepared hole 153b are aligned with the (111) plane along the first direction D1. When anisotropic wet etching is performed on the first flow path arrangement layer 131 and the second flow path arrangement layer 132 in a later step, in a direction orthogonal to the first direction D1, the side walls of the first prepared hole 153a and the second prepared hole 153b are only etched slowly after expanding in accordance with the position of the hard mask film 151. In addition, since the insulating layer 141 remains in the above-described anisotropic wet etching, a (111) plane inclined with respect to the first direction D1 appears in a portion of the hole wall in the vicinity of the insulating layer 141. Therefore, the first prepared hole 153a and the second prepared hole 153b are formed in the substrate 101 being processed, so that the projection portion 300 having the inclined surface of the (111) plane with respect to the nozzle communication flow path 31 and the supply flow path 32 is formed more reliably in a later step.

Next, in an ICP mask removal step ST6, as illustrated in FIG. 9A, a treatment is performed of removing the third photoresist 153 remaining on both surfaces of the substrate 101 being processed with a solvent or the like.

Next, in a first liquid flow path forming step ST7, as illustrated in FIG. 9B, a treatment is performed of removing the portions of the first flow path arrangement layer 131 and the second flow path arrangement layer 132 not covered with the hard mask film 151 by anisotropic wet etching, using an etchant for removing a portion of the first flow path arrangement layer 131 and the second flow path arrangement layer 132. As an etchant for this treatment, an aqueous alkaline solution such as KOH aqueous solution or TMAH aqueous solution can be used. Here, KOH is potassium hydroxide. TMAH is an abbreviation for tetramethylammonium hydroxide. By the anisotropic wet etching, the first prepared hole 153a and the second prepared hole 153b become thick in the nozzle communication flow path corresponding region 151a, and the first prepared hole 153a and the second prepared hole 153b also become thick in the supply flow path corresponding region 151b. At this time, in the vicinity of the insulating layer 141, the inclined surface 301 whose wall surface is the (111) plane is formed. In addition, in the inflow flow path corresponding region 151c, a recess reaching the insulating layer 141 is formed with respect to the first flow path arrangement layer 131, and a recess reaching the insulating layer 141 is formed with respect to the second flow path arrangement layer 132.

FIG. 11 schematically illustrates an example in which the first flow path arrangement layer 131 and the second flow path arrangement layer 132 in the supply flow path corresponding region 151b are etched in the first cross section SC1 along the first direction D1 and the second direction D2. For the sake of clarity, hatching between the first flow path arrangement layer 131 and the second flow path arrangement layer 132 is omitted. In FIG. 11, positions of the first

prepared hole 153a and the second prepared hole 153b are illustrated by two-dot chain lines.

Since the surfaces of the first flow path arrangement layer 131 and the second flow path arrangement layer 132 are (110) planes, portions which are not covered with the hard mask film 151 are etched relatively quickly. In FIG. 11, the states where the first prepared hole 153a and the second prepared hole 153b expands are indicated by arrows.

In the hole expanding from the first prepared hole 153a 10 and the second prepared hole 153b, the front surface of the side wall is along the first direction D1 and is a (111) plane which is hard to etch. In addition, since the insulating layer 141 remains in the anisotropic wet etching, a (111) plane inclined with respect to the first direction D1 appears in a 15 portion of the hole wall in the vicinity of the insulating layer 141. The inclined (111) plane appearing in the second flow path arrangement layer 132 is the second wall surface 341 of the first inclined portion 340 and the third wall surface 351 of the second inclined portion 350 illustrated in FIG. 5. The 20 inclined (111) surface appearing in the first flow path arrangement layer 131 is the fourth wall surface 361 of the third inclined portion 360 illustrated in FIG. 5.

Next, in a third hard mask removing step ST8, as illustrated in FIG. 9C, a treatment is performed of removing a 25 portion of the hard mask film 151 by wet etching using an etchant for removing a portion of the hard mask film 151. For the etchant of this treatment, an aqueous solution of hydrogen fluoride, a mixed solution of hydrogen fluoride and ammonium fluoride, or the like can be used. Here, the 30 portion of the hard mask film 151 in the common liquid chamber corresponding region 151d is removed by etching. As a result, the first flow path arrangement layer in the portion of the first flow path arrangement layer 131 in the common liquid chamber corresponding region 151d is 35 exposed. The portion of the hard mask film 151 other than the common liquid chamber corresponding region 151d is thinned by etching. The insulating layer 141 exposed in the nozzle communication flow path corresponding region 151a, the supply flow path corresponding region 151b, and the inflow flow path corresponding region 151c is thinned or 40 removed by etching.

Next, in a second liquid flow path forming step ST9, as 45 illustrated in FIG. 10A, a treatment is performed of removing the portions of the first flow path arrangement layer 131 and the second flow path arrangement layer 132 not covered with the hard mask film 151 by anisotropic wet etching, using an etchant for removing a portion of the first flow path arrangement layer 131 and the second flow path arrangement layer 132. As an etchant for this treatment, an aqueous alkaline solution such as KOH aqueous solution or TMAH aqueous solution can be used. By the anisotropic wet etching, the first flow path arrangement layer of the first flow path arrangement layer 131 in the common liquid chamber corresponding region 151d is removed until the first flow 50 path arrangement layer reaches the insulating layer 141.

Regarding the hole formed in the supply flow path corresponding region 151b of the second flow path arrangement layer 132 illustrated in FIG. 11, the (111) plane along the first direction D1 and the (111) plane inclined with respect to the first direction D1 are already appeared. Since the etching rate of (111) is slow, the hole is somewhat expanded.

Next, in a fourth hard mask removing step ST10, as 55 illustrated in FIG. 10B, a treatment of removing the hard mask film 151 by wet etching is performed using an etchant for removing the hard mask film 151. For the etchant of this treatment, an aqueous solution of hydrogen fluoride, a mixed solution of hydrogen fluoride and ammonium fluoride, or the

like can be used. Here, the insulating layer **141** exposed in the nozzle communication flow path corresponding region **151a**, the supply flow path corresponding region **151b**, and the inflow flow path corresponding region **151c** is removed by etching. As a result, the nozzle communication flow path **31** is formed in the nozzle communication flow path corresponding region **151a**, the supply flow path **32** is formed in the supply flow path corresponding region **151b**, and the inflow flow path **38** is formed in the inflow flow path corresponding region **151c**. That is, by performing the fourth hard mask removing step **ST10**, the multilayer substrate **30** having the nozzle communication flow path **31**, the supply flow path **32**, the inflow flow path **38**, and the common liquid chamber **40** is obtained.

Thereafter, in order to protect the liquid flow path formed on the multilayer substrate **30** from the liquid, although not illustrated, a protective film forming step may be performed of forming a protective film on the front surface of the liquid flow path formed in the multilayer substrate **30**. As the protective film, a material having liquid resistance such as ink resistance, for example, a material having alkali resistance such as tantalum oxide represented by TaO_x can be used. The thickness of the protective film is not particularly limited, and can be set to approximately 30 to 70 nm.

In order to manufacture the liquid ejecting head **1** from the obtained multilayer substrate **30**, for example, a pressure chamber substrate bonding step, a protective substrate bonding step, a case head bonding step, a nozzle plate bonding step, and a sealing plate bonding step are sufficient. In the pressure chamber substrate bonding step, a treatment is performed of bonding the pressure chamber substrate side surface **30a** of the multilayer substrate **30** to the multilayer substrate side surface **10b** of the pressure chamber substrate **10**. In the protective substrate bonding step, a treatment is performed of bonding the protective substrate side surface **10a** of the pressure chamber substrate **10** to the protective substrate **50**. In the case head bonding step, a treatment is performed of bonding the pressure chamber substrate side surface **30a** of the multilayer substrate **30** to the case head **70**. In the nozzle plate bonding step, a treatment is performed of bonding the nozzle plate side surface **30b** of the multilayer substrate **30** to the nozzle plate **80**. In the sealing plate bonding step, a treatment is performed of bonding the nozzle plate side surface **30b** of the multilayer substrate **30** to the sealing plate **90**. These bonding can be performed using, for example, an adhesive.

By using the SOI substrate for forming the multilayer substrate **30**, the first facing portion **311** including the insulating layer **141** and the second facing portion **312** are formed in the supply flow path **32**, and the inlet portion of the supply flow path **32** protrudes inward compared with the second portion **320**. Since the first wall surface **33a** and the second facing portion **312** of the liquid chamber wall portion **33** are aligned with the position of the insulating layer **141** in the first direction **D1**, the wall surface of the inlet portion of the supply flow path **32** does not have the sagging shape. As a result, since the sagging shape, which is a factor that the supply side inertance varies, is not formed in the supply flow path **32**, the variation of the supply side inertance is reduced, and as a result, the weight variation of the liquid droplet **Q0** from the nozzle **81** is suppressed. Here, when bonding the substrate having the liquid flow path in the first flow path arrangement layer **131** to the substrate having the liquid flow path in the second flow path arrangement layer **132** with an adhesive, it is required to bond these substrates so that the mass of adhesive does not get mixed in the liquid flow path, and a treatment for managing the accuracy of the bonding

position is required. By using the SOI substrate for forming the multilayer substrate **30**, the possibility of the mass of adhesive being mixed in the liquid flow path is eliminated, the accuracy of the position of the liquid flow path is also improved, and the manufacturing cost is suppressed. Furthermore, since the projection portion **300** is aligned with the position of the insulating layer **141**, the dimensional accuracy of the supply flow path **32** is improved, and the characteristics of the liquid ejecting head **1** ejecting the liquid droplet **Q0** are more stabilized. In addition, by adjusting the position of the insulating layer **141** in the first direction **D1**, it is possible to dispose the projection portion **300** at a desired position.

In addition, since the second width **W2** of the second portion **320** in the supply flow path **32** is wider than the first width **W1** of the first portion **310** of the inlet portion, the flow path resistance of the supply flow path **32** does not excessively increase and weight reduction of the liquid droplet **Q0** repeatedly ejected from the nozzle **81** is suppressed.

Furthermore, since the first width **W1** of the inlet portion of the supply flow path **32** is narrower than the second width **W2** of the second portion **320** in the first section **SC1** along the first direction **D1** and the second direction **D2**, the bubble adhering to the wall surface of the inlet portion of the supply flow path **32** is likely to be discharged at the time of cleaning. In addition, since the first inclined portion **340** coupled to the first facing portion **311** is present in the supply flow path **32**, the residual bubbles in the supply flow path **32** are suppressed, and since the second inclined portion **350** coupled to the second facing portion **312** is present in the supply flow path **32**, the residual bubbles in the supply flow path **32** are suppressed. Since the third inclined portion **360** coupled to the first facing portion **311** is present in the extension wall portion **35** of the common liquid chamber **40**, the residual bubbles in the inlet portion of the supply flow path **32** are suppressed.

As described above, according to the manufacturing method of the specific example, variations in the supply side inertance is reduced to suppress the weight variation of the liquid droplets from the nozzle, the decrease in the weight of the liquid droplet repeatedly ejected from the nozzle is suppressed, and the liquid ejecting head which improves the discharge performance of the bubbles of the supply flow path can be obtained.

Various manufacturing methods for forming the projection portion **300** illustrated in FIG. 5 or the like are conceivable.

For example, as in the manufacturing method illustrated in FIG. 12, the first prepared hole **153a** and the second prepared hole **153b** may be formed by laser. In the manufacturing method, the above-described steps **ST4** to **ST6** are replaced by a laser processing step **ST21**.

The cross section of the substrate **101** being processed immediately after performing the above-described steps **ST1** to **ST3** is as illustrated in FIG. 8A. Thereafter, in the laser processing step **ST21**, as illustrated in FIG. 13, a treatment is performed of forming the first prepared hole **153a** and the second prepared hole **153b** penetrating the substrate **101** being processed by being irradiated with laser light **L1** from one surface of the substrate **101** being processed. It may be irradiated with the laser light **L1** onto the substrate **101** being processed from the pressure chamber substrate side surface **30a** or irradiated with the laser light **L1** onto the substrate **101** being processed from the nozzle plate side surface **30b**. When the laser is used, the insulating layer **141** is also

removed in the nozzle communication flow path corresponding region **151a** and the supply flow path corresponding region **151b**.

Thereafter, the multilayer substrate **30** as illustrated in FIG. 10B is formed by the above-described steps ST7 to ST10. In a protective film forming step ST11, a treatment may be performed of forming the protective film on the front surface of the liquid flow path formed in the multilayer substrate **30**.

In addition, as in the manufacturing method illustrated in FIG. 14, a treatment of removing the hard mask film in the common liquid chamber corresponding region **151d** may be performed in a fifth patterning step ST22 after the hard mask forming step ST1. In the manufacturing method, the above-described steps ST2 and ST3 are replaced by the fifth patterning step ST22, and the above-described steps ST7 to ST10 are replaced by a third liquid flow path forming step ST23 and a fifth hard mask removing step ST24. In the example illustrated in FIG. 14, since there is no step of thinning the hard mask film **151**, the hard mask film **151** can be thinned to 50 nm or the like, for example. Although not particularly limited, it is conceivable to form a hard mask film **151** made of silicon nitride on both surfaces of the base substrate **100** by reactive sputtering or the like.

The cross section of the substrate **101** being processed immediately after the hard mask forming step ST1 is performed as is illustrated in FIG. 7B. Thereafter, in a fifth patterning step ST22, as illustrated in FIG. 15A, a treatment is performed of removing the hard mask film in the nozzle communication flow path corresponding region **151a**, the supply flow path corresponding region **151b**, the inflow flow path corresponding region **151c**, and the common liquid chamber corresponding region **151d** in the hard mask film **151**. The fifth patterning step may include a fifth photoresist forming step, a fifth photoresist patterning step, a fifth hard mask removing step, and a fifth photoresist removing step. In the fifth photoresist forming step, a treatment is performed of applying a photoresist on the hard mask film **151** is performed. In the fifth photoresist patterning step, a treatment is performed of removing the above-described regions **151a**, **151b**, **151c**, and **151d** of the photoresist by the exposure or the like. In the fifth hard mask removing step, a treatment is performed of removing the hard mask film **151** in a portion not covered with photoresist by wet etching, using an etchant for removing a portion of the hard mask film **151**. In the fifth photoresist removing step, a treatment is performed of removing the fifth photoresist remaining on the hard mask film **151** with a solvent or the like.

Thereafter, in the steps ST4 to ST6 described above, as illustrated in FIG. 15B, a treatment of forming the first prepared hole **153a** and the second prepared hole **153b** is performed. Next, in the third liquid flow path forming step ST23, as illustrated in FIG. 15C, a treatment is performed of removing the portions of the first flow path arrangement layer **131** and the second flow path arrangement layer **132** not covered with the hard mask film **151** by anisotropic wet etching, using an etchant for removing a portion of the first flow path arrangement layer **131** and the second flow path arrangement layer **132**. By the anisotropic wet etching, the first prepared hole **153a** and the second prepared hole **153b** are thick. In addition, the first flow path arrangement layer **131** of the inflow flow path corresponding region **151c** and the common liquid chamber corresponding region **151d** among the first flow path arrangement layer **131** is removed until the first flow path arrangement layer **131** reach the insulating layer **141**. Furthermore, the second flow path arrangement layer of the inflow flow path corresponding

region **151c** among the second flow path arrangement layer **132** is removed until the second flow path arrangement layer reaches the insulating layer **141**. Next, in the fifth hard mask removing step ST24, a treatment is performed of removing the hard mask film **151** by wet etching, using an etchant for removing the hard mask film **151**. As a result, as illustrated in FIG. 10B, the multilayer substrate **30** having the nozzle communication flow path **31**, the supply flow path **32**, the inflow flow path **38**, and the common liquid chamber **40** is obtained. In the protective film forming step ST11, a treatment may be performed of forming the protective film on the front surface of the liquid flow path formed in the multilayer substrate **30**.

In the manufacturing method illustrated in FIG. 14, since there is no step of thinning the hard mask film **151**, the hard mask film **151** formed in the hard mask forming step ST1 can be thinned and the dimensional accuracy of the nozzle communication flow path **31**, the supply flow path **32**, and the like can be increased.

(5) Specific Example of Liquid Ejecting Apparatus:

FIG. 16 illustrates the appearance of the liquid ejecting apparatus **200** having the above-described liquid ejecting head **1**. The liquid ejecting apparatus **200** illustrated in FIG. 16 is an ink jet type recording apparatus, and is a serial printer. By incorporating the liquid ejecting head **1** into the recording head units **211** and **212**, the liquid ejecting apparatus **200** is manufactured. The liquid ejecting head **1** is attached to each of the recording head units **211** and **212** illustrated in FIG. 16, and ink cartridges **221** and **222** for supplying an ink as a liquid **Q1** to the liquid ejecting head **1** are detachably mounted. A carriage **203** on which the recording head units **211** and **212** are mounted can reciprocate along a carriage shaft **205** attached to an apparatus main body **204**. When the driving force of a driving motor **206** is transmitted to the carriage **203** via a plurality of gears (not illustrated) and a timing belt **207**, the carriage **203** moves along the carriage shaft **205**. The print substrate **290** is transported onto a platen **208** by a paper feed roller (not illustrated) or the like. The liquid droplet **Q0** ejected by the liquid ejecting head **1** supplied with the liquid **Q1** from the ink cartridges **221** and **222** is landed on the print substrate **290** on the platen **208**. As a result, a dot formed by the liquid droplet **Q0** is formed on the print substrate **290**, and a printing image represented by a plurality of dots is formed on the print substrate **290**.

As matter of course, the ink jet type recording apparatus may be a line printer or the like having a line head in which a plurality of nozzles are arranged over the entire width of the print substrate.

(6) Another Specific Example of Liquid Ejecting Head:

FIG. 17 schematically illustrates the first cross section SC1 of the multilayer substrate **30** having a plurality of insulating layers **141**. When the insulating layer **141** is disposed in two layers on the multilayer substrate **30** so as to divide the flow path arrangement layer of the multilayer substrate **30** into three layers, with any one of the insulating layers **141** as a reference, the flow path arrangement layer on the side of the nozzle plate **80** is the first flow path arrangement layer **131** and the flow path arrangement layer on the side of the pressure chamber substrate **10** is the second flow path arrangement layer **132**. In FIG. 17, attention is paid to the insulating layer **141** closer to the nozzle plate **80**, it is illustrated that the first flow path arrangement layer **131**, the insulating layer **141**, the second flow path arrangement layer **132**, the insulating layer **141**, and a third flow path arrangement layer **133** are disposed in this order from the nozzle plate side. In this case, the first facing portion **311** including

the insulating layer 141 closer to the nozzle plate 80 and the first portion 310 including the second facing portion 312 are the first width W1. In the example illustrated in FIG. 17, a pair of projection portions 300 including the insulating layer 141 on the side of the pressure chamber substrate 10 is formed in the middle of the supply flow path 32. Since these projection portions 300 protrude from the second portion 320 to the inside of the supply flow path 32, the rigidity of the wall of the supply flow path 32 is enhanced. The intermediate position of the multilayer substrate 30 in the first direction D1 is not included in the range of the projection portion 300 in the first direction D1 in the multilayer substrate 30.

In the example illustrated in FIG. 17, it is also possible to apply each layer of the multilayer substrate 30 to the third flow path arrangement layer 133, the insulating layer 141, the first flow path arrangement layer 131, the insulating layer 141, and the second flow path arrangement layer 132 in order of arrangement from the nozzle plate 80 side. In this case, a portion including the insulating layer 141 closer to the pressure chamber substrate 10 is applied to the first portion 310.

Even when the plurality of insulating layers 141 are disposed on the multilayer substrate 30, it is possible to obtain the effect of reducing variations in the supplying side inertance, the effect of suppressing decrease in the weight of the liquid droplet repeatedly ejected from the nozzle, and the effect of improving the discharge performance of the bubbles of the supply flow path.

The liquid ejecting head 1 of another example described above can also be used in the liquid ejecting apparatus 200 illustrated in FIG. 16. By incorporating the liquid ejecting head 1 into the recording head units 211 and 212, the liquid ejecting apparatus 200 is manufactured.

FIG. 18 schematically illustrates a step of manufacturing the liquid ejecting head 1 when the multilayer substrate 30 having the liquid flow path has the plurality of insulating layers. In the manufacturing step illustrated in FIG. 18, a laser processing step ST31 is roughly added to the above-described steps ST1 to ST6 and ST7 to ST11. The details of the steps ST1 to ST6 and ST7 to ST11 illustrated in FIG. 18 are the same as the above-mentioned steps, so a detailed description will be omitted. FIGS. 19A, 19B, 20A, 20B, 21A, 21B, 22A, and 22B schematically illustrate the above-described method of forming the multilayer substrate 30.

For the sake of convenience, a cross section of the substrate is illustrated at a position passing through the projection portion 300 in a positional relationship in which the multilayer substrate 30 illustrated in FIG. 17 is turned upside down. For the sake of clarity, elements appearing behind are omitted, and the ratio of the thickness of each layer may be different from the actual ratio. For convenience of description, an example is illustrated in which the first flow path arrangement layer 131, the insulating layer 141, the second flow path arrangement layer 132, a second insulating layer 142, and the third flow path arrangement layer 133 are applied in order of arrangement from the nozzle plate 80 side. Here, the second insulating layer 142 is an element of a name for convenience to distinguish it from the insulating layer 141 closer to the nozzle plate 80, and is an element that can be an insulating layer included in the first portion 310.

FIG. 19A illustrates a cross section of the base substrate 100 for forming the multilayer substrate 30 having the liquid flow path. When the base substrate 100 is an SOI substrate, the first flow path arrangement layer 131, the second flow path arrangement layer 132, and the third flow path arrangement layer 133 are made of silicon, and the insulating layer

141 and the second insulating layer 142 are made of silicon oxide. The orientations of crystals of the first flow path arrangement layer 131, the second flow path arrangement layer 132, and the third flow path arrangement layer 133 are matched with each other. The nozzle plate side surface 30b which is the front surface of the first flow path arrangement layer 131 is a (110) plane, and the pressure chamber substrate side surface 30a which is the front surface of the third flow path arrangement layer 133 is also a (110) plane.

First, in the hard mask forming step ST1, a treatment is performed of forming a hard mask film 151 on the pressure chamber substrate side surface 30a and the nozzle plate side surface 30b, which are front surfaces of the base substrate 100. Next, in the first patterning step ST2, a treatment is performed of removing the hard mask film in the nozzle communication flow path corresponding region 151a corresponding to the nozzle communication flow path 31, the supply flow path corresponding region 151b corresponding to the supply flow path 32, and the inflow flow path 20 corresponding region 151c corresponding to the inflow flow path 38 in the hard mask film 151. Next, in the second patterning step ST3, as illustrated in FIG. 19B, a treatment is performed of thinning the hard mask film in the common liquid chamber corresponding region 151d corresponding to the common liquid chamber 40 in the hard mask film 151.

Next, in the ICP mask forming step ST4, a treatment is performed of disposing the third photoresist 153 on a portion of the pressure chamber substrate side surface 30a and the nozzle plate side surface 30b which is the front surface of the substrate 101 being processed, except for the plurality of prepared holes. Next, in the prepared hole forming step ST5, as illustrated in FIG. 20A, a treatment is performed of forming the first prepared hole 153a and the second prepared hole 153b in the substrate 101 being processed. Here, the first prepared hole 153a reaching the insulating layer 141 is formed in the first flow path arrangement layer 131 from the nozzle plate side surface 30b of the substrate 101 being processed. The second prepared hole 153b reaching the second insulating layer 142 is formed in the third flow path arrangement layer 133 from the pressure chamber substrate side surface 30a of the substrate 101 being processed. Next, in the ICP mask removal step ST6, a treatment is performed of removing the third photoresist 153 remaining on both surfaces of the substrate 101 being processed with a solvent or the like.

Between the first prepared hole 153a and the second prepared hole 153b, the insulating layer 141, the second flow path arrangement layer 132, and the second insulating layer 142 are left. Therefore, in the laser processing step ST31, as illustrated in FIG. 20B, a treatment is performed of penetrating between the first prepared hole 153a and the second prepared hole 153b by being irradiated with laser light L1 from one surface of the substrate 101 being processed. It may be irradiated with the laser light L1 onto the substrate 101 being processed from the pressure chamber substrate side surface 30a or irradiated with the laser light L1 from the nozzle plate side surface 30b onto the substrate 101 being processed.

Next, in the first liquid flow path forming step ST7, as illustrated in FIG. 21A, a treatment is performed of removing the first flow path arrangement layer 131 and the third flow path arrangement layer 133 in a portion not covered with the hard mask film 151 by an anisotropic wet etching using an etchant. The above-described etchant is a solution for removing a portion of the first flow path arrangement layer 131 and the third flow path arrangement layer 133. By the anisotropic wet etching, the first prepared hole 153a and

the second prepared hole **153b** become thick, and in the vicinity of the insulating layer **141** and the second insulating layer **142**, the inclined surface **301** whose wall surface is the (111) plane is formed. In addition, in the inflow flow path corresponding region **151c**, a recess reaching the insulating layer **141** is formed with respect to the first flow path arrangement layer **131**, and a recess reaching the second insulating layer **142** is formed with respect to the third flow path arrangement layer **133**.

Next, in the third hard mask removing step **ST8**, as illustrated in FIG. 21B, a treatment is performed of removing a portion of the hard mask film **151** by wet etching, using an etchant for removing a portion of the hard mask film **151**. Here, the portion of the hard mask film **151** in the common liquid chamber corresponding region **151d** is removed by etching. In addition, in the third hard mask removing step **ST8**, a treatment is performed so as to remove a portion of the insulating layer **141** and the second insulating layer **142** in the inflow flow path corresponding region **151c**.

Next, in the second liquid flow path forming step **ST9**, as illustrated in FIG. 22A, a treatment is performed of removing the first flow path arrangement layer **131**, the second flow path arrangement layer **132**, and the third flow path arrangement layer **133** in a portion not covered with the hard mask film **151**, the insulating layer **141**, and the second insulating layer **142** by an anisotropic wet etching using an etchant. The above-described etchant is a solution for removing a portion of the first flow path arrangement layer **131**, the second flow path arrangement layer **132**, and the third flow path arrangement layer **133**. By the anisotropic wet etching, the first flow path arrangement layer of the first flow path arrangement layer **131** in the common liquid chamber corresponding region **151d** is removed until the first flow path arrangement layer reaches the insulating layer **141**, and the second flow path arrangement layer of the inflow flow path corresponding region **151c** of the second flow path arrangement layer **132** is removed.

Next, in the fourth hard mask removing step **ST10**, as illustrated in FIG. 22B, a treatment is performed of removing the hard mask film **151** by wet etching, using an etchant for removing the hard mask film **151**. Here, the insulating layer **141** exposed in the common liquid chamber corresponding region **151d** and the inflow flow path corresponding region **151c** is removed by etching. In addition, the second insulating layer **142** exposed in the inflow flow path corresponding region **151c** is also removed by etching. By performing the fourth hard mask removing step **ST10**, the multilayer substrate **30** having the nozzle communication flow path **31**, the supply flow path **32**, the inflow path **38**, and the common liquid chamber **40** is obtained. Thereafter, in the protective film forming step **ST11**, a treatment may be performed of forming a protective film on the front surface of the liquid flow path formed in the multilayer substrate **30**.

Even with the above-described manufacturing method, variations in supply side inertance are reduced, a reduction in weight of liquid droplets repeatedly ejected from the nozzles is suppressed, and the discharge performance of the bubbles in the supply flow path is improved.

(7) Application Example and Modification Example:

The present disclosure can be applied to various applications and various modifications.

For example, the liquid ejecting apparatus is not limited to a printing apparatus dedicated to printing, and may be a facsimile apparatus, a copying apparatus, a multifunction machine having a function other than printing such as facsimile or copying, or the like.

The liquid ejected from the fluid ejecting head includes a fluid such as a solution in which a solute such as a dye is dissolved in a solvent and a sol in which solid particles such as a pigment or a metal particle are dispersed in a dispersion medium. Such liquids include ink, liquid crystal, and the like. The liquid ejecting apparatus includes an apparatus for manufacturing a color filter for a liquid crystal display, an apparatus for manufacturing an electrode for an organic EL display, a biochip manufacturing apparatus, a manufacturing apparatus for forming wiring of a wiring substrate, and the like, in addition to the image recording apparatus such as a printer. Here, the organic EL is an abbreviation for organic electroluminescence.

In the above-described embodiment, although both the first facing portion **311** and the second facing portion **312** protrude inward compared with the second width **W2** in the supply flow path **32**, one of the first facing portion **311** and the second facing portion **312** may not protrude inward. As long as the first width **W1** of the first portion **310** is narrower than the second width **W2** of the second portion **320**, the bubble attached to the wall surface of the inlet portion of the supply flow path **32** is likely to be discharged at the time of cleaning.

In the above-described embodiment, although the first inclined portion **340** and the second inclined portion **350** are disposed in the supply flow path **32**, and the third inclined portion **360** is disposed in the common liquid chamber **40**, a case where a portion or all of these inclined portions **340**, **350**, and **360** is absent is also included in the present technology. Even in this case, as long as the first width **W1** of the first portion **310** is narrower than the second width **W2** of the second portion **320**, the bubble attached to the wall surface of the inlet portion of the supply flow path **32** is likely to be discharged at the time of cleaning.

In the above-described embodiment, although the second wall surface **341** of the first inclined portion **340**, the third wall surface **351** of the second inclined portion **350**, and the fourth wall surface **361** of the third inclined portion **360** are the (111) planes, a case where these wall surfaces **341**, **351**, and **361** deviate from the (111) plane is also included in the present technology. Even in this case, as long as the first width **W1** of the first portion **310** is narrower than the second width **W2** of the second portion **320**, the bubble attached to the wall surface of the inlet portion of the supply flow path **32** is likely to be discharged at the time of cleaning. The first angle **AN1** and the second angle **AN2** for specifying the position of the first portion **310** are not limited to acute angles and may be right angle or obtuse angle. Even when these angles **AN1**, **AN2** are right angles or obtuse angles, the cross section shape of the inlet portion of the supply flow path **32** is close to a circle due to the existence of the first portion **310**, so that the residual bubbles in the supply flow path **32** are suppressed.

In the above-described embodiment, although the insulating layer **141** is not left in the first wall surface **33a** and the second facing portion **312**, a case where the insulating layer **141** remains in the first wall surface **33a** and the second facing portion **312** is also included in the present technology. Even in this case, as long as the first width **W1** of the first portion **310** is narrower than the second width **W2** of the second portion **320**, the bubble attached to the wall surface of the inlet portion of the supply flow path **32** is likely to be discharged at the time of cleaning.

(8) Additional Aspects:

The present technology also has the following additional aspects. The parenthesis written in the additional aspect illustrates the reference numeral of the element correspond-

31

ing to the above-described specific example. As matter of course, each element of the additional aspect is not limited to the specific example indicated by the reference numeral.

Additional Aspect 1

A manufacturing method of a flow path substrate (30) having the nozzle communication flow path 31 disposed between the nozzle plate 80 having the nozzle 81 and the pressure chamber substrate 10 having the first pressure chamber 121 to allow the first pressure chamber 121 and the nozzle 81 communicate with each other, in which the pressure chamber substrate 10 has the second pressure chamber 122 disposed next to the first pressure chamber 121 via the partition wall 12a, the flow path substrate (30) has the common liquid chamber 40 communicating with the first pressure chamber 121 and the second pressure chamber 122, the base substrate 100 for forming the flow path substrate (30) includes the first flow path arrangement layer 131, the insulating layer 141 having a material different from a material forming the first flow path arrangement layer 131, and the second flow path arrangement layer 132 having a material different from a material forming the insulating layer 141, in order of arrangement from the nozzle plate 80 side, the flow path substrate (30) includes the liquid chamber wall portion 33 disposed on the side of the second flow path arrangement layer 132 from the common liquid chamber 40, the flow path substrate (30) has the supply flow path 32 via which the common liquid chamber 40 communicates with the first pressure chamber 121, the direction from the common liquid chamber 40 to the first pressure chamber 121 is defined as the first direction D1, and the direction intersecting the first direction D1 is defined as the second direction D2, the method includes a first forming step of forming the substrate 101 being processed having the prepared holes (153a, 153b) thinner than the supply flow path 32 in the region (151b) corresponding to the supply flow path 32 from the base substrate 100, and a second forming step of forming the first portion 310 having the first width W1 at the inlet portion of the supply flow path and the second portion 320 having the second width W2 wider than the first width W1 in the first cross section SC1 along the first direction D1 and the second direction D2 of the supply flow path 32, by aligning the position of the inlet portion of the supply flow path 32 from the common liquid chamber 40 with the position of the insulating layer 141 by performing anisotropic wet etching on the substrate 101 being processed.

Here, the first forming step corresponds to steps ST1 to ST6 illustrated in FIGS. 7B, 7C, 8A to 8C, and 9A, steps ST1 to ST3 and ST21 illustrated in FIG. 12, steps ST1, ST22, and ST4 to ST6 illustrated in FIG. 14, steps ST1 to ST6, and ST31 illustrated in FIG. 18, and the like. The second forming step corresponds to steps ST7 to ST10 illustrated in FIGS. 9B, 9C, 10A and 10B, steps ST7 to ST10 illustrated in FIG. 12, steps ST23 and ST24 illustrated in FIG. 14, steps ST7 to ST10 illustrated in FIG. 18, and the like.

According to above Additional Aspect 1, it is possible to provide the flow path substrate for the liquid ejecting head that improves the discharge performance of the bubbles of the supply flow path.

Additional Aspect 2

A manufacturing method of a liquid ejecting head 1 including a pressure chamber substrate bonding step of bonding the pressure chamber substrate 10 to the front surface (30a) of the flow path substrate (30) on the side of the pressure chamber substrate 10 obtained by the manufacturing method according to Additional Aspect 1, and a

32

nozzle plate bonding step of bonding the nozzle plate 80 to the front surface (30b) on the side of the nozzle plate 80 of the flow path substrate (30).

According to above Additional Aspect 2, it is possible to provide the liquid ejecting head that improves the discharge performance of the bubbles of the supply flow path.

Additional Aspect 3

A manufacturing method of a liquid ejecting apparatus 200, including a liquid ejecting head incorporating step of incorporating the liquid ejecting head obtained by the manufacturing method according to Additional Aspect 2 into the liquid ejecting apparatus 200.

According to above Additional Aspect 3, it is possible to provide the liquid ejecting apparatus including the liquid ejecting head for improving the discharge performance of the bubbles of the supply flow path.

(9) Conclusion:

As described above, according to the present disclosure, it is possible to provide a technology such as the liquid ejecting head that improves the discharge performance of the bubbles of the supply flow path according to various aspects. As matter of course, the basic operation and effect described above can be obtained even with a technology formed only of the constituent features according to the independent aspect.

In addition, a configuration in which each of the configurations disclosed in the above examples are mutually replaced or the combination is changed, a configuration in which each of the configurations disclosed in the related art and the above examples are mutually replaced or the combination is changed, and the like can also be implemented. The present disclosure includes these configurations and the like.

What is claimed is:

1. A liquid ejecting head comprising:
a nozzle plate that includes a nozzle;
a multilayer substrate that includes a first flow path arrangement layer and a second flow path arrangement layer in an order of arrangement from a side of the nozzle plate, and that includes a nozzle communication flow path and a common liquid chamber; and
a pressure chamber substrate that includes a first pressure chamber communicating with the nozzle via the nozzle communication flow path and a second pressure chamber disposed next to the first pressure chamber via a partition wall, wherein
the common liquid chamber communicates with the first pressure chamber and the second pressure chamber, the multilayer substrate includes a liquid chamber wall portion disposed on a side of the second flow path arrangement layer from the common liquid chamber, the liquid chamber wall portion includes a first wall surface facing the common liquid chamber, the multilayer substrate includes a supply flow path via which the common liquid chamber communicates with the first pressure chamber and which has an inlet portion coupled to the first wall surface, when a direction from the common liquid chamber toward the first pressure chamber is defined as a first direction and a direction intersecting the first direction is defined as a second direction, the supply flow path includes a first portion having a first width in the inlet portion and a second portion having a second width in a first cross section along the first direction and the second direction,

the first width is narrower than the second width, and the supply flow path includes:

- a first inclined portion having a second wall surface inclined with respect to the first direction between the first portion and the second portion; and
  - a second inclined portion having a third wall surface inclined with respect to the first direction between the first portion and the second portion.
2. The liquid ejecting head according to claim 1, wherein the multilayer substrate includes an insulating layer having a material different from a material forming the first flow path arrangement layer and a material forming the second flow path arrangement layer between the first flow path arrangement layer and the second flow path arrangement layer,
- the first portion includes a first facing portion protruding inside the supply flow path compared with the second portion at a position including the insulating layer, and the first inclined portion having the second wall surface extends between the first facing portion and the second portion.
3. The liquid ejecting head according to claim 2, wherein the first portion includes a second facing portion protruding inside the supply flow path from the liquid chamber wall portion at a position facing the first facing portion.
4. The liquid ejecting head according to claim 3, wherein the second inclined portion having the third wall surface extends between the second facing portion and the second portion.
5. The liquid ejecting head according to claim 2, wherein a range from the insulating layer to the first inclined portion in the first direction includes an intermediate position in the first direction in the multilayer substrate.
6. The liquid ejecting head according to claim 1, wherein a shape of the second portion in a second cross section orthogonal to the first direction has a first angle and a second angle facing the first angle, and
- the first inclined portion is disposed in a direction opposite to the first direction from the first angle.
7. The liquid ejecting head according to claim 6, wherein the first angle and the second angle are acute angles.
8. The liquid ejecting head according to claim 1, wherein a shape of the second portion in a second cross section orthogonal to the first direction has a first angle and a second angle facing the first angle,
- the first inclined portion is disposed in a direction opposite to the first direction from the first angle, and
- the second inclined portion is disposed in a direction opposite to the first direction from the second angle.

9. The liquid ejecting head according to claim 1, wherein the first inclined portion is separated from a coupling portion between the supply flow path and the first pressure chamber.
10. The liquid ejecting head according to claim 1, wherein the first flow path arrangement layer and the second flow path arrangement layer are made of silicon, a plane index of a front surface of the multilayer substrate is (110), and
- a plane index of a wall surface of the first inclined portion is (111).
11. The liquid ejecting head according to claim 1, further comprising:
- a sealing plate bonded to the multilayer substrate as a portion of a wall of the common liquid chamber.
12. The liquid ejecting head according to claim 1, wherein the pressure chamber substrate includes a vibration plate including a portion of a wall of the first pressure chamber and a piezoelectric element disposed on the vibration plate.
13. The liquid ejecting head according to claim 1, wherein the multilayer substrate includes an insulating layer having a material different from a material forming the first flow path arrangement layer and a material forming the second flow path arrangement layer between the first flow path arrangement layer and the second flow path arrangement layer.
14. The liquid ejecting head according to claim 1, wherein the first portion includes a first facing portion protruding inside the supply flow path compared with the second portion, and
- the first inclined portion having the second wall surface extends between the first facing portion and the second portion.
15. The liquid ejecting head according to claim 14, wherein
- the first portion includes a second facing portion protruding inside the supply flow path from the liquid chamber wall portion at a position facing the first facing portion.
16. The liquid ejecting head according to claim 15, wherein
- the second inclined portion having the third wall surface extends between the second facing portion and the second portion.
17. A liquid ejecting apparatus comprising:
- the liquid ejecting head according to claim 1.
